[57] CLAIM

The ornamental design for a reflector for a recessed
ceiling lighting fixture, as shown and described.

DESCRIPTION

FIG. 1 is a bottom plan view of a reflector for a re-
cessed ceiling lighting fixture showing my new design;
FIG. 2 is a side elevational view thereof, all sides being
identical;

FIG. 3 is a bottom perspective view thereof;

FIG. 4 is a top, side, and end perspective view thereof.
